HINGE

La Verne E. Clayton, Rockford, Ill., assignor to Amerock Corporation, Rockford, Ill., a corporation of Illinois

Filed July 28, 1965, Ser. No. 86,341

Term of patent 14 years

(Cl. D10—9)

FIG. 2 is an enlarged perspective view.

FIG. 3 is an enlarged side view of the hinge as viewed from the left in FIG. 1.

FIG. 4 is a sectional view taken along the line 4—4 in FIG. 3.

The drawings are stippled to indicate a contrasting surface color or texture.

The dominant features reside in the solid line portion.

I claim:

The ornamental design for a hinge, substantially as shown and described.
